W. H. WHIGHAM.

BIT BRACE.

APPLICATION FILED MAR. 28, 1910.

970,361.

Patented Sept. 13, 1910.

UNITED STATES PATENT OFFICE.

WILLIAM H. WHIGHAM, OF CALIFORNIA, PENNSYLVANIA.

BIT-BRACE.

970,361.

Specification of Letters Patent. Patented Sept. 13, 1910.

Original application filed February 7, 1910, Serial No. 542,638. Divided and this application filed March 28, 1910. Serial No. 552,061.

To all whom it may concern:

Be it known that I, WILLIAM H. WHIGHAM, a citizen of the United States of America, residing at California, in the county of Washington and State of Pennsylvania, have invented certain new and useful Improvements in Bit-Braces, of which the following is a specification, reference being had therein to the accompanying drawing.

10 This invention relates to bit braces and the object thereof is to provide a bit brace in the manner as hereinafter set forth which is particularly adapted for use in connection with the form of angle guide attachment as disclosed in my co-pending application, Serial No. 542,638, filed Feb. 7, 1910, and of which this application is a division.

Although the bit brace forming the subject-matter of this application is designed 20 for use in connection with the form of angle guide attachment referred to, yet it is to be understood that the bit brace can be used for any purposes and in connection with any angle guide attachment wherein the bit 25 brace is found applicable.

A further object of the invention is to provide a bit brace in the manner as herein-after set forth whereby an angle guide attachment can be connected thereto when 30 boring horizontally upwardly, downwardly or in any angle.

Further objects of the invention are to provide a bit brace in the manner as herein-after referred to and for the purpose set 35 forth and which shall be simple in its construction, strong, durable, efficient in its use, allowing for the convenient connecting therewith of the angle guide attachment, and inexpensive to manufacture.

40 With the foregoing and other objects in view, the invention consists of the novel construction, combination and arrangement of parts as hereinafter more specifically described and illustrated in the accompanying drawings wherein is shown one embodiment 45 of the invention, but it is to be understood that changes, variations and modifications can be resorted to which come within the scope of the claim hereunto appended.

50 In the drawings wherein like reference characters denote corresponding parts throughout the several views, Figure 1 is an elevation of a bit brace in accordance with

this invention showing the adaptation therewith of angle guide attachment and the bit 55 in position for boring downwardly at an angle, Fig. 2 is an elevation showing the bit brace in position for boring upwardly at an angle and with the angle guide attachment connected thereto, Fig. 3 is a sectional detail 60 broken away of one end of the brace, and Fig. 4 is a like view of the other end of the brace.

In Fig. 1 of the drawing the bit as well as the brace is shown disposed at an angle 65 for boring downwardly at an angle as indicated by the broken line *a* with respect to the perpendicular, as indicated by the broken line *b*.

In Fig. 2 of the drawing the brace and bit 70 are shown disposed at an angle for boring upwardly at an angle, as indicated by the broken line *c* with respect to the perpendicular, as indicated by the broken line *d*.

The angle guide attachment is referred to 75 generally by the reference character *A* and embodies a base *B* formed with a screw-threaded stem *C*.

A bit brace in accordance with this invention comprises a yoke shaped brace having 80 the free terminus of its arm 5 offset, as at 6 and the free terminus of its arm 7 offset, as at 8. The brace 4 is provided with a hand grip 9. The offset portion 6 of the arm 5 has connected to the outer face at its free 85 end a grip or rest 10 and the offset portion 8 of the arm 7 has connected to and projecting from a chuck 11 provided with a bit 12. The offset portion 6 has formed in its inner face at the free end thereof a threaded 90 socket 13 and the offset portion 8 has its inner face at its free end provided with a screw threaded socket 14. The socket 13 opposes the socket 14 and each of said sockets has the axis thereof in alinement 95 with the axis of the bit 12.

When boring downwardly or horizontally, the angle guide attachment is coupled to the inner face of the offset portion 8 by the engagement of the threaded stem *C* with the 100 threaded wall of the socket 14 and when boring upwardly the angle guide attachment is secured to the inner face of the offset portion 6 by the engagement of the threaded stem *C* with the threaded wall of the 105 socket 13.

The offsetting of the free ends of the arms 5, 7 is had to prevent the operator's hand engaging the attachment in using the brace.

What I claim is:—

- 5 A bit brace having the free ends of each of its arms offset outwardly, said offset portions being oppositely disposed with respect to each other and each having its inner face at its outer end provided with a screw-
10 threaded socket, an angle guide attachment, coupled to the brace by one of said threaded

sockets, said sockets opposing each other and the axis of each of the sockets being in alignment with each other and with the axis of the bit coupled with the brace.

15

In testimony whereof I affix my signature in the presence of two witnesses.

WILLIAM H. WHIGHAM.

Witnesses:

FRED M. WHIGHAM,
ALBERT D. COATSWORTH.
